UNITED STATES PATENT OFFICE.

FRANK R. STAFFORD, OF PROVIDENCE, RHODE ISLAND, ASSIGNOR TO THE
WAITE, THRESHER COMPANY, OF SAME PLACE.

DESIGN FOR A HANDLE FOR BUTTON-HOOKS, &c.

SPECIFICATION forming part of Design No. 28,553, dated May 10, 1898.

Application filed February 25, 1898. Serial No. 671,696. Term of patent 3½ years.

To all whom it may concern:

Be it known that I, FRANK R. STAFFORD, a citizen of the United States, residing at Providence, in the State of Rhode Island, have invented and produced a new and original Design for a Handle for Button-Hooks or Similar Articles, of which the following is a specification, reference being had to the accompanying drawings, forming a part thereof.

Figure 1 represents a side view of a handle showing my improved design. Fig. 2 represents a longitudinal section of the handle.

As shown in the drawings, the leading or material features of my design consist in the transverse circular bead *a* at the end of the handle, the raised scrolls *b b*, foliated at their ends adjacent to the bead *a* and having the bead *c* between the said foliated ends, the rows of graduated beads *e e* between the scrolls *b b* and the boundary edges *ff* of the handle, with the three-leaved ornament *g*, having the bead *h* at its base, the two-leaved ornament *i* and the opposite beads *j j* between the said ornaments and the centrally-arranged row of beads *k*, the beaded scrolls *ll* at the opposite sides of the oval convex panel *m*, the

shell ornament *n* arranged between the scrolls *o o*, which are turned outwardly at their inner ends within the outer scrolls *o' o'*, and the shell ornaments *p p' p' p* at the outer end of the handle. The shell ornament *n* is provided at its inner end with the terminating knob or bead *n'*, and the bead *r* is arranged between the bead *n'* and the inwardly-turned ends of the scrolls *ll*, and the beads *s s* are arranged at the opposite edges of the handle between the scrolls *o' o'* and the scrolls *ll*.

The handle at its wider portions is thicker at its central line than at its edges, a central longitudinal section being represented in Fig. 2.

Having now described my invention, what I claim as new, and desire to secure by Letters Patent, is—

The design for a handle for button-hooks and similar articles, herein shown and described.

FRANK R. STAFFORD.
